(57) CLAIM

The ornamental design for an angel in bowl figurine, as shown and described.

DESCRIPTION

The file of this patent contains at least one drawing executed in color. copies of the patent with color drawing(s) will be provided by the Patent and Trademark Office upon request and payment of the necessary fee.

FIG. 1 is a perspective view of an angel in bowl figurine in accordance with my design;

FIG. 2 is front view thereof;

FIG. 3 is a top plan view thereof;

FIG. 4 is a right side view, thereof;

FIG. 5 is a back view, thereof;

FIG. 6 is a bottom plan view, thereof;

FIG. 7 is a left side view thereof;

FIG. 8 is a perspective view of an angel in accordance with my design;

FIG. 9 is front view of the angel of FIG. 8;

FIG. 10 is a top plan view of the angel of FIG. 8;

FIG. 11 is a right side view of the angel of FIG. 8;

FIG. 12 is a back view of the angel of FIG. 8;

FIG. 13 is a bottom plan view of the angel of FIG. 8;

FIG. 14 is a left side view of the angel of FIG. 8;

FIG. 15 is a perspective view of a bowl in accordance with my design;

FIG. 16 is a top plan view of the bowl of FIG. 15;

FIG. 17 is a bottom plan view of the bowl of FIG. 15; and, FIG. 18 is a front view of the bowl of FIG. 15, the rear view, right side view, and left side view being mirror images thereof.

In FIGS. 8-18, the angel and the bowl have been shown separately for clarity of illustration.

The color shown on the claimed design forms no part thereof.
